BUILDER MOTION

Albert E. Winslow, Mystic, Conn., assignor, by
mesne assignments, to Farrel-Birmingham
Company, Incorporated, Ansonia, Conn., a cor-
poration of Connecticut

Application March 24, 1943, Serial No. 480,351

7 Claims. (Cl. 242—43.7)

This invention relates to a builder motion for yarn packages and is illustrated as applied to a spinning machine.

In the usual builder motion provided on a spinning frame, the traverse for the yarn which is wound upon the package is of uniform length which shifts to progressively higher positions on the vertically wound package until the package is completed. In the winding of yarn in this manner the convolutions of yarn will lay one on top of another in such a manner that the package will sluff or the windings of yarn slide one upon the other and become loose.

One of the objects of this invention is to provide a yarn package in which the yarn will be so wound that one convolution of yarn will not be directly on top of another so as to permit of a sluffing of the yarn and an upsetting of the package.

Another object of the invention is to provide a traverse motion so that there will be a non-frequent repeat of the manner in which the yarn is laid upon the package.

A more specific object of the invention is to vary the traverse of the yarn making it non-uniform to prevent the laying of the convolutions of one layer of yarn directly over those of the layer below it.

Another object of this invention is to provide a constant and gradual change of traverse as distinguished from a step by step change.

Another object of the invention is to provide an arrangement whereby the range of traverse may be varied in length by a simple adjustment of the parts.

Another object of the invention is to provide a variable traverse motion in which the parts may be well lubricated.

With these and other objects in view, the invention consists of certain novel features of construction, as will be more fully described and particularly pointed out in the appended claims.

In the accompanying drawings:

Figure 1 is an elevation showing a builder motion arm equipped with my invention, the frame of a spinning machine being fragmentally shown with the drive through which power is being dotted;

Figure 2 is a sectional view taken substantially on line 2—2 of Fig. 4;

Figure 3 is a diagrammatic view illustrating the builder arm, the main cam for operating it and the mechanism at the end of the arm through which the arm is connected to the ring rail for imparting a traverse motion thereto;

Figure 4 is a view in the nature of a top plan view showing parts in section to better bring out their relationship and expose the relatively movable operating parts;

Figure 5 is a section on line 5—5 of Figure 4;

Figure 6 is a section on line 6—6 of Figure 4; and

Figure 7 is a section on line 7—7 of Figure 4; and

Figure 8 is an elevation of the yarn package formed.

This invention may be viewed as an attachment to the usual rockable arm of a spinning frame through which the builder motion operates. The builder arm is rocked in the usual manner by a cam provided for this purpose. Instead of connecting the arm directly to the ring rail by means of a sprocket chain or the like I interpose between the arm and the chain an arrangement which in effect varies the length of traverse of the ring rail. The variation continually changes over a range of traverse which varies in length thereby providing a maximum and minimum length for operation. This maximum and minimum length, however, may be additionally changed by an adjustment which is provided while the traverse itself may also be adjusted by lengthening the main arm or in effect the point of attachment of the chain along the main arm.

With reference to the drawings 10 designates the supporting framework structure of the spinning frame from which there projects a bracket 11 (see Figs. 1 and 5) having bearings 12 and 13 to rotatably support a shaft 14 upon which the hub 15 of the builder motion arm 16 is pivotally mounted (see Fig. 4). This arm has an extension designated generally 17 thus providing this arm in two pieces. Upon the upper surface of the arm 16 bosses 18 and 19 are raised (see Figs. 4 and 7) to rotatably support a cam follower 20 by means of trunnions 21 extending from either side thereof. The main operating cam 22 (see Figs. 1 and 2) engages this cam follower and is secured to a shaft 23 which is mounted in the bearing 24 extending from the frame 10. This shaft 23 is driven by a gear 25 engaging the spiral pinion gear 26 on the drive shaft 27 which extends downwardly from the train of gears at the head end of the spinning frame.

The portion 17 of the builder motion arm comprises a member 30 (see Figs. 4 and 6) which has recesses 31 to fit the boss 32 which extends inwardly from the arm 16 and thus provides a track along which this member 30 may slide.

Suitable slots 33 and 34 are provided in the member 30 through which bolts 35 and 36 extend to bind the member 30 in position. A boss 37 is provided on the arm 16 through which a threaded set screw 38 may extend to be adjusted by means of a head 39 and held in position by the binding nut 40. The end 41 of this screw provides an adjustable abutment for the end 30 of the arm 17 and may be utilized to force the arm 17 outwardly to extend the length of the arm 16.

The outer end of the arm member 17 consists of a bearing annulus 45 into which there is received a guide member 46 which may be rocked to any relatively angular position of rotation in the bearing annulus 45 and there held in position by the bolts 47 threaded into the guide member 46 and provided with washers 48 beneath their heads 49 to engage the annulus for binding the guide member in position. On the inner surface of the member 46 there are provided parallel guideways 50 for directing the movement of a slide 51 which slide provides a suitable bearing as at 52 (see Fig. 2) for a cam follower 53 which is carried by the slide. The cam follower is supported at the other end in a bearing 54 provided in a yoke 55 which is attached through a chain 56 to mechanism for reciprocating the ring rail. The chain 56 is connected to a drum 57 keyed to shaft 58 to oscillate this shaft 58 while complementary chains 59 extend from other drums 60 at as many points as is desired from the shaft to links 61 which conveys reciprocatory movement to the ring rail of the spinning machines or to any other part which may act as a traverse for the yarn if some other form of traverse than a ring and traveller is provided. A skeleton framework 65 (see Figs. 2 and 4) is supported from the guide member 46 and extends upwardly to provide a bearing 66 for a shaft 67 upon which a cam 68 is fixed for engagement with the cam follower 53. This bearing 66 extends through the yoke 55 which will be readily apparent from Figure 2. This framework also supports a boss 69 in which the shaft 70 is rotatably mounted for the support of a worm gear as will presently appear. This shaft 70 has its axis coaxial with the center of the annulus or bearing 45.

The cam 68 is driven from the main cam 22 by the gear 71 mounted on the shaft 23 which drives by sprocket chain 73 the gear 72 mounted on the shaft 14 upon which the builder motion arm 16 is pivotally mounted.

A shaft 74 has a bearing 75 (see Figure 1) secured to the arm 16 and also a bearing 76 supported as at 77 from the portion 17 of this arm and movable therewith. This bearing may be independently adjusted with this portion 17 by reason of the slots 77' and bolt 78 by which this bearing is secured to the part 17. The shaft 74 is driven by the spiral gears 79 on the shaft 14 and 80 on the shaft 74. This shaft 74 is provided with splines which slidably engage complementary grooves in gear 80 and has abutment collars 81 and 82 engaging the bearing 76 while it drives the worm gear 83 which in turn drives the worm gear 84 on the shaft 70 and spiral gear 85 keyed to shaft 67 which transmits motion through this shaft 67 to the cam 68.

In operation the main drive shaft 21 will operate the cam 22 which will engage cam follower 20 to force the builder arm 16 and its complementary part 17 which is connected to the ring rail downwardly, the weight of the ring rail serv-

ing to keep the cam follower 20 in engagement with the cam 22 at all times. This causes the usual movement of the builder arm. This usual movement of the builder is varied by the cam 68 which is carried by the builder motion arm and constantly rotated at a lesser speed from the main cam through gear 71, chain 73, gear 72, shaft 14, gears 78 and 80, shaft 74, gears 83, 84, and 85, and shaft 67. The movement of the cam is transmitted through follower 53 to slide 51 and yoke 55 to which the chain 56, rock shaft 58 and chain 59 supply the connection from the builder arm to the ring rail. By this arrangement, the traverse which may heretofore have been five and one-half inches with the cam 22 alone will be varied so that it will be from five and three-eighths to five and five-eighths inches with much less opportunity for a repeat to occur in the lay of the yarn on the package. For relatively small diameter yarn such as glass yarn, a ratio of 20 to 1 between cams 22 and 68 has been found satisfactory. A ratio of 40 to 1 has been found satisfactory for relatively coarser worsted yarn. However, this may be varied if desired.

If it is desired to additionally lengthen or shorten the traverse this may be done by loosening bolts 35-36 and sliding the part 17 with reference to the part 16 and adjusting the screw 38 to the proper position. After this adjustment has been made it is clamped in position by the nuts 35 and 36. Since the bearing 76 is fixed to the arm 17 adjustment of arm 17 along the arm 16 will not disturb the relationship between the gears carried by the shaft 74 and arm 17.

The length of the traverse may also be conveniently regulated by inclining the guide carrying member 46 with reference to the builder motion arm. The guideways 50 may be rotated in the annulus 45 from the position, such as illustrated in Fig. 3, so that their guiding edges will be parallel to a line 90 shown dotted in Fig. 3. This adjustment carries with it supporting bracket frame 65 which pivots around the shaft 70 as a center and also carries with it the cam and gear 68. By movement to the inclined position illustrated in Fig. 3 by dotted line 90 the length of the traverse will be increased while by inclining the guides in the opposite direction to the dotted line 91 the length of the traverse will be decreased. If desirable, indicating means showing a plus and minus graduated amounts may be provided on the annulus 45 and guide carrying member 46 that the desired adjustment may be had. The diagrammatic showing in Fig. 3 will make plain the relative motions which have been above described.

In Fig. 8 I have illustrated a package 95 having ends 96 tapered which is the form of package desired to be wound on the spinning frame equipped with the builder motion above described. The layers of the yarn will be sufficiently irregular so that one convolution will not lie above another and there will be a long interval probably several layers before there is a repeat. Thus, the yarn is more firmly wound upon the package and will not sluff off.

I claim:

1. In a builder motion for a spinning frame or the like a pivot member, an arm rockably mounted thereon, a cam follower carried by said arm, driving means including a cam engaging said follower for rocking said arm, a guideway carried by said arm and a slide movable in said guideway, an auxiliary cam follower carried by said slide, means for connecting said cam fol-

lower to a yarn guide, a second cam carried by said arm for engaging said auxiliary follower, and means operated from the driving means for the first cam for rotating said second cam.

2. In a builder motion for a spinning frame or the like, a shaft, an arm rockably mounted thereon, a cam follower carried by said arm, driving means including a cam engaging said follower for rocking said arm, a guideway carried by said arm and a slide movable in said guideway, an auxiliary cam follower carried by said slide, means for connecting said cam follower to a yarn guide, a second cam carried by said arm for engaging said auxiliary follower, means operated from the driving means for the first cam for rotating said shaft, and means operated by said shaft for rotating said second cam.

3. In a builder motion for a spinning frame or the like a shaft, an arm rockably mounted thereon, a cam follower carried by said arm, driving means including a cam engaging said follower for rocking said arm, a guideway carried by said arm and a slide movable in said guideway, an auxiliary cam follower carried by said slide, means for connecting said cam follower to a yarn guide, a second cam carried by said arm for engaging said auxiliary follower, means operated from the driving means for the first cam for rotating said shaft, a second shaft movable with said arm and driven from the first shaft, and means driven by said second shaft for rotating said second cam.

4. In a builder motion for a spinning frame or the like a shaft, an arm rockably mounted thereon, a cam follower carried by said arm, driving means including a cam engaging said follower for rocking said arm, a guideway carried by said arm and a slide movable in said guideway, an auxiliary cam follower carried by said slide, means for connecting said cam follower to a yarn guide, a second cam carried by said arm for engaging said auxiliary follower, means operated from the driving means for the first cam for rotating said shaft, a second shaft movable with said arm and driven from the first shaft, a worm at the end of said second shaft, means for rotatably mounting in said arm, said guideway and slide, a gear carried by said rotatable

mounting for said guideway and rotatable about the axis of said rotatable mounting and engaging said worm on the end of said shaft, and means driven by said gear for rotating said second cam.

5. In a builder motion for a spinning frame or the like a shaft, an arm rockably mounted thereon, a cam follower carried by said arm, driving means including a cam engaging said follower for rocking said arm, a guideway carried by said arm and a slide movable in said guideway, an auxiliary cam follower carried by said slide, means for connecting said cam follower to a yarn guide, a second cam carried by said arm for engaging said auxiliary follower, and means operated from the driving means for the first cam for rotating said shaft, a second shaft movable with said arm and driven from the first shaft, a worm at the end of said second shaft, means for rotatably mounting in said arm said guideway and slide therein, a second cam and a gear for driving the same, a gear carried by said rotatable mounting for said guideway and rotatable about the axis of said rotatable mounting and engaging said worm on the end of said shaft, and a gear on said rotatable mounting for conveying motion from said shafts to said second cam while permitting inclination of said guideway.

6. In a builder motion for a spinning frame or the like having a yarn guide, a pivot member, an arm rockably mounted thereon, means for rocking said arm about said pivot member, means including a slide carried by said arm through which the arm is connected to said yarn guide, and means independent of the rocking of said arm for reciprocating said slide relative to the arm during the movement thereof.

7. In a builder motion for a spinning frame or the like having a yarn guide, a pivot member, an arm rockably mounted thereon, means for rocking said arm about said pivot member, means including a cam operated slide carried by said arm through which the arm is connected to said yarn guide, and means independent of the rocking of said arm for rotating said cam for reciprocating said slide relative to the arm during the movement thereof.

ALBERT E. WINSLOW.
